UNITED STATES PATENT OFFICE.

MAX JUST AND FRANZ HEINRICH WITTIG, OF WERDAU, AND MAX SEYFERTH, OF CRIMMITSCHAU, GERMANY.

ATTIC-WINDOW.

968,480.

Specification of Letters Patent. Patented Aug. 23, 1910.

Application filed March 25, 1910. Serial No. 551,539.

To all whom it may concern:

Be it known that we, MAX JUST and FRANZ HEINRICH WITTIG, residing at Werdau, and MAX SEYFERTH, residing at Crimmitschau, i. Sa., Germany, subjects of the German Empire, have invented a new and useful Improvement in Attic-Windows; and we do hereby declare the following to be a full, clear, and exact description of the same.

10 Our invention relates to attic windows.

The inwardly-opening attic windows known heretofore have the disadvantage that water, snow or the like can readily pass into the attic or garret through the gaps between the boxing and the sash, and no device is arranged at the same which would suitably lead away rain or the like which runs in.

A primary object of our invention is to 20 provide an attic window which prevents rain and so on penetrating into the attic, it being simultaneously guaranteed that the rain flows away readily.

Our invention is represented by way of 25 example in the accompanying drawing, wherein:

Figure 1 is a vertical section through our improved attic window, and Fig. 2 is a detail view of a modification.

30 Referring to the drawing, the bottom strip or sill b' of the boxing arranged in well-known manner is substantially lower than the three strips or lintel and jambs b^2 of the boxing, the upper parts of which are 35 enlarged on the inside. Grooves d are provided in these enlarged portions c . Instead of the enlarged portions provided with grooves inverted U-bars a or the like may be soldered or riveted to the strips b^2 , as 40 shown in Fig. 2.

The front, bottom strip e' of the downwardly-opening window frame or sash e rocking around a pivot e^3 is formed as a weather-board f which runs along the top 45 edge of the strip b' and projects over the latter when the window is closed. The other sides and end e^2 of the sash project over the inserted pane g and, as indicated by dotted lines, enter into the grooves d when the 50 window is shut, so that no water, etc., can enter into the attic, and the water, etc., falling onto the window runs away over the weather-board f which covers the gap between the

bottom end e' of the sash and the boxing so that no water, etc., can enter here.

55

A notched bar i is pivoted on a pivot i' inserted in the aperture in the roof, and on a lug k' on the sash is provided a pin k which is placed into one of the notches for optionally adjusting the window, while for 60 fixing the window in its closed position a spring-pressed bolt h is provided. For protecting the window we provide on the boxing a grate, lattice or Venetian blind l which can be opened and closed independently of 65 the window, and when closed prevents to some extent the penetration of soot, insects and the like into the attic when the window is open.

We claim:

70

1. The combination, with a roof having a window aperture, of a boxing secured at the aperture, said boxing having a sill lower than the jambs and lintel thereof having inwardly-enlarged, inwardly grooved upper 75 portions, and an inwardly-opening sash pivoted at the sill and entering into the grooves in the boxing in its closed position, the lower end of the sash being formed as a weather-board projecting over the sill.

80

2. The combination, with a roof having a window aperture, of a boxing secured at the aperture, said boxing having a sill lower than the jambs and lintel thereof having inwardly-enlarged, inwardly grooved upper 85 portions, and an inwardly-opening sash pivoted at the sill and entering into the grooves in the boxing in its closed position, the lower end of the sash being formed as a weather-board projecting over the sill, a protecting 90 device adapted to be opened and closed independently of the window mounted on the boxing, and notched means pivotally secured to the roof and operatively connected with the sash for holding the sash in its open 95 position.

In testimony whereof, we have signed our names to this specification in the presence of two subscribing witnesses.

MAX JUST.
FRANZ HEINRICH WITTIG.
MAX SEYFERTH.
